METHOD OF AND APPARATUS FOR MAKING
BRUSHES

Ruben O. Peterson, University Heights, Ohio, assignor to The Osborn Manufacturing Company, Cleveland, Ohio, a corporation of Ohio

Application September 20, 1948, Serial No. 50,108

21 Claims. (Cl. 300—21)

1

The present improvements, relating as indicated to brush manufacture, have more particular regard to the manufacture of so-called brush strip. This as is well known is a form of brush element capable of being assembled into various types of brushes, either flat, circular or cylindrical, as desired, such element consisting of a folded or doubled layer of brush material, the doubled or bent portion of which is secured in a suitable base.

According to the present commercial practice such brush elements of the type in question are made by feeding a continuous layer of brush material, cut to length, onto a continuous flat strip, a wire or equivalent retaining member being applied to such layer opposite such strip, and the latter being thereupon folded longitudinally so as correspondingly to fold such brush material about said retaining member. One practical form of apparatus for carrying out such method of manufacture will be found illustrated and described in U. S. Patent No. 1,963,045 to F. J. Bickel, dated June 12, 1934, and in my prior Patent No. 2,303,386, dated December 1, 1942, there is shown and described an improved form of backing strip adapted to be utilized in the method and apparatus of said Bickel patent. It will be noted that the backing strip in the case of each of the foregoing patents is characterized by being formed with integral teeth which project inwardly when the strip is folded into channel form so as to overlie and lock in place the retaining element about which the brush material is folded or looped.

In my co-pending application, filed November 9, 1943, Serial No. 509,585, now Patent No. 2,449,668, September 21, 1948, of which this application is a continuation-in-part, I disclose an improvement in the method of making brush strip such as described which consists, briefly stated, in winding a continuous length of stranded brush material about a mandrel so as to constitute a stranded layer presenting two oppositely directed folds. Each such folded portion of the layer is then secured to a base of general channel form or otherwise, and such layer of brush material then is severed along lines parallel with but removed from such bases so that two brush strips are provided.

One object of the present invention is to provide an improved apparatus and method for making two or more such brush strips continuously, i. e. without interruption in the supply of the brush material or the other components such as the retaining wire and base strip. Another ob-

2

ject is to provide for the use in such continuous method and apparatus of channel base strip provided with projections or teeth which lock or hold the retaining member in place. Still another object is to provide an apparatus which may be readily adapted to the making of brush strip of greater or less width as desired and for supplying the brush material in the form of a thicker or thinner layer as desired to correspondingly vary the thickness of such brush strip.

To the accomplishment of the foregoing and related ends, said invention, then consists of the means hereinafter fully described and particularly pointed out in the claims, the annexed drawings and the following description setting forth in detail certain means and one mode of carrying out the invention, such disclosed means and mode illustrating, however, but one of various ways in which the principle of the invention may be used.

In said annexed drawings:

Fig. 1 is a plan view more or less diagrammatic in character of one end of a mechanism or apparatus embodying my present improvements;

Fig. 2 is a similar plan view constituting in effect a continuation of the plan view of Fig. 1;

Fig. 3 is a side elevation of a portion of said apparatus shown in plan in Fig. 1;

Fig. 4 is similarly a side elevation substantially of the portion of said apparatus shown in plan in Fig. 2;

Fig. 5 is a transverse section of said apparatus taken on the plane indicated by the line 5—5 Fig. 2;

Fig. 6 is another transverse section taken on the plane indicated by the line 6—6, Fig. 2;

Fig. 7 is a detail section similar to that of Fig. 6, but taken a short distance to the left thereof as indicated by the line 7—7, Fig. 2;

Fig. 8 is a transverse section on the plane indicated by the line 8—8, Fig. 2; and

Figs. 9, 10 and 11 are sectional views corresponding with those of Figs. 5, 6 and 7, but showing certain modifications in construction.

The brush material *b*, as previously indicated, will be in the form of strands of indefinite length. Such strands may be of any material suitable for use in brushes, by which term it is intended to include devices such as mops and the like. Thus they may consist of wires either single or multiple and twisted or untwisted. Likewise they may consist of fibrous cords twisted and otherwise formed and treated, if desired, in various known ways to modify the action thereof in the finished brush.

Such stranded brush material is supplied to the brush making mechanism or apparatus from one or more spools 1, two being shown in Fig. 1. The brush material is first led onto a rotatable spindle including a drum portion 2 by rotation of arm 2' carrying brush material supply spools 1, 1, at its respective ends. Arm 2' is rotatably mounted on a hollow shaft 3' journaled in suitable bearings 3, 3, and provided with a pulley 4' whereby it may be driven in either direction as desired.

Drum 2 is adapted to be driven by pulley 4 through a hollow stub shaft internally concentric with the drive for arm 2'. As explained below, such drum will normally be rotated only for purposes of compensating for inequalities resulting from any slight differential between the rate at which the stranded material is wound on and unwound from such drum.

The aforesaid mounting for arm 2' and drum 2 together with their respective drive means is provided with a bore 5 through which the brush material retaining wires a, two in number as illustrated, are supplied to the brush making operation. These wires are drawn from corresponding spools 6, 6 and an uninterrupted supply may be achieved by attaching the leading end of a wire on the new spool to the trailing end of the wire on a nearly exhausted spool.

Aligned with the end of brush material feed drum 2 opposite that to which the wires a are supplied is a shaft 7 rotatably mounted in suitable bearings 8, 8 and carrying a pulley 9 whereby it may be driven in either direction and at such rate of speed as desired. Such drive for shaft 7 will be synchronized with the drive for arm 2' so that such shaft will rotate at the same rate of rotation as such arm. Shaft 7 is provided with a central bore 10 through which the wires a after passing through the drum are axially conducted to and beyond the further end of said shaft. The shaft is also provided with a second bore or longitudinally extending passage 11 disposed to one side, i. e. eccentrically of the axis of the shaft, it being through this latter bore or passage that the brush material b is conducted lengthwise of the shaft and beyond the further end thereof.

The drive for drum 2 will preferably be by means of an electric motor provided with any standard form of speed control device so that the rotation thereof may be regulated in the manner hereinafter indicated. However, any other well-known form of drive and speed regulator appropriate thereto may be employed.

On the end of shaft 7 adjacent drum 2 an arm 12 is mounted so as to be capable of swinging movement toward and from the axis of the shaft. The outer end of such arm overlies the brush material feed drum 2 and is provided with a guide 13 through which the brush material after being wound several times around the drum is guided into the passage or bore 11 in shaft 7. As will be presently explained in describing the operation of the mechanism as a whole, the circumference of brush material feed drum 2 is designed to be approximately equal to the length of one turn of brush material as wound into the layer from which the brush strips are fashioned. Since, however, in practice the length of such turn will vary, particularly where one turn surrounds another previously applied turn, it becomes desirable, as previously indicated, to vary the rate of rotation of drum 2 and thus the rate of feed of the brush material to the mechanism. This is conveniently accom-

plished by mounting on shaft 7 adjacent the inner end of arm 12 micro-switches 14 which are connected with the motor or other drive for drum 2 whereby the speed of rotation of the latter will be automatically varied as the arm 12 swings in and out. Said arm, due to centrifugal action, normally tends to fly outwardly as it is rotated along with the shaft 7 on which it is mounted, such tendency being restrained by the tension of the stranded brush material b passing through guide 13 in the outer end of the arm on its way from the drum 2 to the winding mechanism. Accordingly the construction of the switch 14 and its connection with the before-mentioned speed regulator is such that as the arm moves outwardly the drum 2 will be rotated in one direction to reduce the rate at which brush material is unwound therefrom and when said arm moves inwardly to operate the other switch 14 the drum will be rotated in the other direction to increase the rate at which such material is paid off. When the rate of withdrawal of the stranded brush material from drum 2 is exactly balanced by the rate at which such material is wound upon the mandrel, neither of such micro-switches will be operated and drum 2 will then be stationary. Drum 2 will desirably have a slight taper or fillet in the region where the brush material is wound thereon in order to facilitate axial shifting of the coils on such drum toward the end of the unwinding arm 12. This arrangement permits the strands b to be unwound from the spools 1, 1 and eventually wound about mandrel M without any twisting or snarling. When the width of the mandrel is altered, a new drum 2 will be substituted in the mechanism selected so that the circumference of such drum equals the length of one turn of the brush material about such mandrel.

The end of shaft 7 opposite to that on which arm 12 is mounted is provided with a suitable guide arm 15, shown as consisting of a bent tube which constitutes in effect a continuation of the bore or passage 11, whereby the stranded brush material b is conducted to a point well beyond the end of the shaft and lying a substantial distance radially from the axis of the shaft, such last-mentioned distance being determined by the maximum width of the layer into which the brush material is to be wound, or in other words, of the mandrel M which extends in alignment with the end of the shaft in question for such distance as will be required to accommodate the various mechanisms associated with the winding operation and the securing to the resulting folded portions of the wound brush material layer B of the particular type of element employed to secure the bases of the resulting brush strips B', B' (see Fig. 2).

The specific detailed structure of the so-called mandrel M, such numeral designating such structure generally, will be found illustrated in Figs. 4 to 6 inc. As there shown, such mandrel comprises two main elements 16 and 17 consisting of two contiguously aligned bars or flat plates disposed at right angles to each other. These parts are of sufficient strength and are so connected together at their adjoining ends that the mandrel as a whole will be self-sustaining when supported at its respective ends. Such support at the left-hand end (see Fig. 1) is afforded by an extension 18 formed to receive one end of a tubular core 19 that extends through shaft 7 and provides the bore 10 through which retaining

wires *a* are conducted to the mandrel. The other, or right-hand end, of said mandrel, as indicated in Fig. 2, will be attached to a suitable standard *20* or like fixed support.

Associated with member *16* of the mandrel are two parallel rails *21*, *21* held in spaced relation to the respective sides of said member and approximately equi-distantly therefrom by means of a series of oppositely extending arms *22*, *22* of adjustable length. The rails *21* are preferably of triangular cross section as shown in Fig. 5, becoming flattened further along, and the outwardly directed edge or apex of each is formed with a longitudinally extending groove *23* adapted to receive and form a guide for the corresponding wire or equivalent brush material retaining element *a*. Each of the upper and lower edges of member *16* is likewise formed with a groove *24* which is adapted to receive and guide corresponding runs of an endless belt or cord *25* mounted so as to travel lengthwise in the same direction along said grooves *24* as do the wires *a* in grooves *23*.

The grooves *23* in the rails *21* are sufficiently shallow so that the wires *a* when received therein will extend beyond such grooves, and the same is true of the grooves *24* and such traveling cord or belt *25* which will preferably be of circular cross section, as shown in Fig. 5. Accordingly, when the stranded brush material is wound around the portion of the mandrel comprising member *16* and laterally spaced rails *21*, the resulting layer will take the form more or less of a parallelogram which contacts at its four corners with, and is supported by, such wires and travelling cord. The latter, it will be understood, is driven so as to travel in unison with the movement of the wires, and along with the latter constitutes means for conveying the layer of brush material from the point where the same is deposited on the mandrel at its left-hand end towards the other end at a uniform rate of speed.

In order that the two runs of the conveyor belt or cord *24* may, as indicated, travel in the same direction along the respective upper and lower edges of mandrel *16*, such cord is passed around two pairs of pulleys or sheaves *30*, *30* and *31*, *31*, which are rotatably mounted at each end of said mandrel. One of each of said pair of sheaves serves as an idler around which reverse runs of the cord pass entirely clear of engagement with mandrel member *16*. In order to drive the conveyor cord in synchronism with the movement of the wires *a* along the mandrel, each of the pulleys *30* is connected by means of suitable gearing *32* with one of several sheaves *33* on the mandrel extension *18* around which sheaves the wires are caused to pass following their emergence from the bore *10* in shaft *7* in order that they may be spread sufficiently apart to be brought into alignment with the grooves *23* in rails *21*.

Mandrel member *17*, which as previously stated is disposed at right angles to the member *16* along which conveyor or belt *25* travels, constitutes in effect an extension of rails *21*. Indeed up to points *35* (see Fig. 2) said member is of the same width as the distance spanned by the apices of said rails and like them formed with grooves *36* adapted to receive and guide the wires or retaining members *a*. However, beyond points *35* continuing to the right-hand end of said member *17* the respective lateral edges thereof are cut away so that from such points onward the

wires will travel clear of contact with the edges in question, i. e. there will be a limited space left between such wires and edges for the interruption of elements on the channel *C* which forms the bases of the finished brush channel *B'*.

Such channel bases *C*, as previously indicated, will preferably be of the construction shown and described in my prior Patent No. 2,303,386 in that the side walls thereof will have teeth *c* punched inwardly therefrom so as to overlie the retaining member *a* and lock the same in place as illustrated in Fig. 6.

The present mechanism is designed to fashion such channel bases from strip *C'* of flat stock and apply the same to the respective doubled portions of the layer of brush material *B* as the latter is conveyed along the mandrel *M*. To this end spools *37* of such strip stock are disposed one on each side of the machine, conveniently adjacent the left-hand end of the mandrel *M* (see Fig. 1). From such reels each strip is first passed through a continuously operating punch *38* which forms the projections *c* therein while the strip remains otherwise in its original flat condition. Following such punching operation the strip is next passed through a series of forming rolls *39*, *40* and *41* whereby it is formed into a channel with flaring side walls, the flare being somewhat greater than that illustrated in Fig. 7, so that when by means of angularly related guide rolls *42* and *43* such partially formed strip is brought into contact with the corresponding folded portion of the layer *B* of brush material on the mandrel *M*, such portions with the retaining wire *a* therein will freely enter the channel strip. Such engagement occurs just beyond the end of mandrel member *16* at which point opposed rolls *44* are located, one pair on each side of the mandrel, which are adapted to engage the side walls of the channel and press the same together until the inwardly directed teeth or projections *c* penetrate through the brush material and contact with the respective upper and lower faces of mandrel member *17*. As the layer of brush material continues its movement to the right, beyond the points *35* where member *17* is narrowed as previously described, each of the respective channel strips is engaged by a second pair of rolls *45* which further compress the side walls so as to bring the teeth or projections *c* into the interlocking relation illustrated in Fig. 6. If desired, a third pair of rolls *46*, one on each side of mandrel member *17*, may be provided which further engage and finally form the side walls of the channel strip to provide a base *C* of desired cross-section and securely attach the same to the corresponding folded portion of the brush material layer *M*. The foregoing pairs of rolls *44*, *45* and *46*, and particularly the last, serve furthermore as traction means whereby the layer of brush material is moved continuously at a uniform rate from left to right through the mechanism.

Just beyond the series of rolls last described, the layer of brush material is severed longitudinally on both sides of the mandrel along lines midway of the folded edge portions to which the channel bases have been applied. Such severing means *50* are only diagrammatically shown in the drawings, it being understood that they may take on various forms such as that of a rotary cutter, flying shear, or the like, depending upon the character of the brush material composing the layer that is to be severed. In order further to flatten out the layer and retain the strands

thereof in position during the severing operation, one or more pairs of pressure rolls 51 are mounted above and below the mandrel adjacent the point where the severing occurs, the pairs of rolls being axially aligned and one being located on one side and the other on the other of the line of the cut.

The appearance of the brush layer immediately after it has been thus severed and before it has left the mandrel is shown in Fig. 8 where there is also diagrammatically illustrated a safety switch lever 52. The latter is mounted, as about a pivotal axis 53, so as normally to project through a slot 54 in the mandrel and thus be engaged by any strand of brush material that may escape the severing device. Such lever is operatively connected with a suitable switch, not shown, whereby operation of the machine as a whole is stopped in the event the lever is actuated in the manner just referred to. Thus the attention of the operator will be called to the failure of the slitting device, which can then be adjusted.

In Fig. 2 the respective sections of the severed brush layer are shown as being bent laterally, i. e. away from each other, in contact with guide rolls 55, whereby the brush strips which such sections now constitute may be directed onto corresponding mandrels or drums similar to those shown in the aforementioned Bickel Patent No. 1,963,045. Such arrangement will be particularly suitable where the brush strip is to be made into a cylindrical brush by being wound helically upon a mandrel, and where, as would necessarily be the case, the mandrel is rotated under power, it will constitute additional traction means, supplementing the action of rolls 44, 45 and 46 in pulling the layer of brush material as it is wound about the mandrel as well as the finished strips through the machine.

Where instead of thus winding the brush strip in the form of a helix about a mandrel it is desired to use such strip in straight form, the two severed portions of the wound layer of brush material may be carried in a straight line to the right instead of being directed outwardly as shown in Fig. 2, and such strips then be cut off to form sections of any desired length. It will also be understood that where the brush strip is withdrawn and wound in spiral form successive convolutions may be cut to provide circular or annular brush sections.

The modification in construction illustrated in Figs. 9, 10 and 11 has principally to do with the construction of that portion of the mandrel along which the brush material wound on such mandrel is carried in open looped form, i. e. before it is flattened and severed to constitute the two finished brush strips. In such modified construction, instead of employing a vertically disposed bar or flat plate from which to support the rails that guide the wires *a*, a member 60 of the cross-sectional form clearly shown in Figs. 9 and 10 is substituted. The rails 61 furthermore are flat instead of V-shaped although adjustably supported from the central member 60 by such means as bolts 62, as before.

Said member 60, it will be noted, in addition to being formed with longitudinally extending grooves 63 to guide the two forwardly moving runs of the endless belt or cord 25 is also provided with adjacent spaced grooves 64 which are adapted to receive and guide the return runs of such belt or cord. Furthermore, such grooves 63 instead of being located opposite each other,

are displayed laterally so that the loop formed of the brush material wound around the mandrel assumes the form of a flattened parallelogram. At the same time the support provided for the return runs of the belt or cable by the grooves 64 serves to keep such runs from slapping against the brush material as thus wound on the mandrel.

In each of the two forms of mandrel construction which have been described, the proper spacing between the two retaining wires *a* is maintained by adjustment of the rails 21 or 61 as the case may be. Furthermore, said rails are so formed that the wires will be held slightly farther apart at the left-hand end of the mandrel where the brush material is wound around the latter than at the right-hand end, so that there will be a correspondingly slight relaxation of tension in the loops which comprise the layer of brush material. The speed at which the wires *a*, *a* are drawn by the previously described traction means provided at the right-hand end of the machine will of course determine the density of the layer of brush material wound on the mandrel for any given rate of speed of rotation of the shaft 7 which winds the material upon the mandrel through guide arm 15. Accordingly, by properly correlating these two speeds a thicker or thinner layer of brush material, as desired, will be left doubled about the wires at the stage in the operation where the bases of the brush strips are formed.

In the particular construction of machine illustrated it is only necessary that the conveyor belt or cord 25 should convey the brush material to the stage in the operation where the teeth in the channel base are caused to engage the folded portions of the layer of brush material formed by the winding operation. However, if a different form of securing means for the base is utilized, it will be necessary to carry such belts to the point at which the brush material is firmly secured to the retaining wires, by whatever means employed.

My present improved method of manufacturing brush strip has the obvious advantage of simultaneously producing two such strips. These ordinarily will be identical although by shifting the line of the slitting operation nearer the one base than the other the width of the one strip may be made correspondingly narrower. In any case, the present method eliminates entirely the preliminary operation of cutting the stock of brush material into short lengths and distributing them into an even layer before they are doubled and attached to the retaining wire or equivalent member. Even more important is the elimination of the waste which is involved by reason of the necessity for trimming the material where thus cut into short lengths and then doubled before being secured to the retaining member; by the present procedure the ends of the strands in the respective strips are perfectly cut square across. As a result of the foregoing a very considerable reduction in labor cost is also effected, while at the same time an improved product is obtained.

Instead of continuously winding brush material about drum 2 and then unwinding the same, it is obvious that such drum may instead constitute a spool on which a supply of material has previously been wound, but in such case it will of course be necessary more frequently to replenish or replace such spool. Also, instead of permanently attaching the brush material to the continuous retaining members it may be de-

sired, in the construction of mop elements, for example, to secure the wound brush material in its folded condition and join adjacent portions thereof to form a continuous element by means of adhesive or stitching, continuous conveying means equivalent to wires *a* being utilized about which the material is wound and transported to the point of securing. This application is a continuation-in-part of my co-pending application Serial No. 668,390, filed May 9, 1946, now abandoned.

Other modes of applying the principle of the invention may be employed, change being made as regards the details described, provided the features stated in any of the following claims or the equivalent of such be employed.

I therefore particularly point out and distinctly claim as my invention:

1. In a method of making a brush element of the type wherein stranded brush material is looped upon an extended retaining member, the steps which consist in supporting limited sections of a plurality of such members of indefinite length in substantially parallel, spaced relation, moving such sections of said members longitudinally in unison, winding the brush material around such sections of said members thus spaced and while thus moving, movingly supporting the wound brush material intermediately of said members by supporting means traveling therewith, progressively securing such brush material to said members as wound thereon, and then severing such wound brush material along lines lying intermediately of said members.

2. In a method of making a brush element of the type wherein stranded brush material is looped upon an extended retaining member, the steps which consist in supporting limited sections of a plurality of such members of indefinite length in substantially parallel spaced relation, moving such sections of said members longitudinally in unison, winding the brush material around such sections of said members thus spaced and while thus moving, such brush material being initially wound in relatively open loops, to minimize frictional contact with the retaining member supporting means, gradually flattening such loops with the brush material doubled around said members, progressively securing such brush material to said members as wound thereon, and then severing such wound brush material along the lines lying intermediately of said members.

3. In a method of making a brush element of the type wherein stranded brush material is looped upon an extended retaining member, the steps which consist in supporting limited sections of a plurality of such members of indefinite length in substantially parallel spaced relation, moving such sections of said members longitudinally in unison, winding the brush material around such sections of said members thus spaced and while thus moving, such brush material being initially wound in relatively open loops, to minimize frictional contact with the retaining member supporting means, gradually flattening such loops with the brush material doubled around said members, progressively closing a channel-form strip upon each such doubled portion of the brush material and enclosed member and then severing such brush material along lines lying intermediately of said members.

4. In a method of making a brush element of the type wherein stranded brush material is looped upon an extended retaining member, the steps which consist in supporting limited sections

of a plurality of such members of indefinite length in substantially parallel spaced relation, moving such sections of said members longitudinally in unison, winding the brush material around such sections of said members thus spaced and while thus moving, such brush material being initially wound in relatively open loops to minimize frictional contact with the retaining member supporting means, gradually flattening such loops with the brush material doubled around said members, progressively closing a channel-form strip upon each such doubled portion of the brush material and enclosed member and then severing such brush material along lines lying intermediately of said members, such channel-form strip having inwardly directed projections and such closing step interlocking the same behind said retaining member before such strip is completely closed.

5. In a machine for continuous manufacture of a brush element of the type described, the combination of a mandrel adapted to support two continuously moving elongated brush material retaining members in substantially parallel spaced relation, means adapted to wind stranded brush material around said mandrel and members, and means supporting the loops of brush material intermediately of said members and adapted to travel in the same direction in association therewith.

6. In a machine for continuous manufacture of a brush element of the type described, the combination of a mandrel adapted to support two continuously moving elongated brush material retaining members in substantially parallel spaced relation, means adapted to wind stranded brush material around said mandrel and members, and a belt on each side of said mandrel extending intermediately of said members and traveling in the same direction, whereby the loops of brush material as wound upon the mandrel are wholly movably supported.

7. In a machine for continuous manufacture of a brush element of the type described, the combination of a mandrel adapted to support two continuously moving elongated brush material retaining members in substantially parallel spaced relation, means adapted to wind stranded brush material around said mandrel and members, and a belt on each side of said mandrel extending intermediately of said members and traveling in the same direction, whereby the loops of brush material as wound upon the mandrel are wholly movably supported, said belt being operatively interconnected with said members so as to travel in unison therewith.

8. In a machine for continuous manufacture of a brush element of the type described, the combination of a mandrel adapted to support two continuously moving wires in substantially parallel spaced relation, means adapted to wind stranded brush material around said mandrel and wires, and a belt on each side of said mandrel extending intermediately of said wires and traveling in the same direction, whereby the loops of brush material as wound upon the mandrel are wholly movably supported, said belt on each side of said mandrel gradually approaching the plane defined by said wires, whereby the loops of brush material are permitted to gradually flatten as they are carried along said mandrel.

9. In a machine for continuous manufacture of a brush element of the type described, the combination of a mandrel adapted to support two continuously moving wires in substantially

11

parallel spaced relation, and means adapted to wind stranded brush material around said mandrel and wires, said means including a rotatable shaft at one end of said mandrel aligned with the axis of winding and having an axial passage through which the aforesaid members are led to said mandrel and a second, parallel passage through which the brush material is led, a radial arm on said shaft extending over such mandrel end, and guides on said arm adapted to lead brush material drawn through such second passage first outwardly and then inwardly to the point of winding.

10. In a machine for continuous manufacture of a brush element of the type described, the combination of a mandrel adapted to support two continuously moving wires in substantially parallel spaced relation, and means adapted to wind stranded brush material around said mandrel and wires, said means including a rotatable shaft at one end of said mandrel aligned with the axis of winding and having a longitudinal passage, a radial arm on said shaft extending over such mandrel end, guides on said arm adapted to lead brush material drawn through such passage first outwardly and then inwardly to the point of winding, and an independently driven drum aligned with said shaft, the brush material being wound about such drum before being led to such passage.

11. In a machine for continuous manufacture of a brush element of the type described, the combination of a mandrel adapted to support two continuously moving wires in substantially parallel spaced relation, and means adapted to wind stranded brush material around said mandrel and wires, said means including a rotatable shaft at one end of said mandrel aligned with the axis of winding and having a longitudinal passage, a radial arm on said shaft extending over such mandrel end, guides on said arm adapted to lead brush material drawn through such passage first outwardly and then inwardly to the point of winding, and an independently driven drum aligned with said shaft, the brush material being wound about such drum before being led to such passage, and means operated by the tension on such brush material adapted to control the direction of rotation of said drum.

12. In a machine for manufacture of brush elements and the like, the combination of a drum from which continuous brush material may be unwound, a member adjacent said drum adapted to rotate about the same axis as said drum and through which such continuous material may be conducted, eccentric guide means on said member adapted to guide such material from said drum through said member, continuous conveying means travelling in a direction axial of such drum, further eccentric guide means on said member adapted to wind brush material conducted therethrough about said conveying means, and means for securing such wound brush material to maintain it in folded condition and join adjacent portions thereof to form a continuous element.

13. In a machine for continuous manufacture of a brush element of the type described, the combination of a stationary mandrel adapted to guide the longitudinal movement of a wire along its exterior, means operative to move such wire along said mandrel, a tubular shaft rotatably mounted substantially axially of one end of said mandrel, a drum from which a continuous strand of brush material may be unwound rotatably

12

mounted axially of the other end of said shaft from said mandrel, means on the end of said shaft adjacent said drum adapted to guide a strand of brush material from said drum into said tubular shaft, means on the end of said shaft adjacent said mandrel adapted to wind such strand conducted thereto through said shaft about said mandrel and such brush material wire, means for rotating said shaft, means for rotating said drum, means for securing such brush material to such wire, and means for severing such brush material along a line spaced from such wire.

14. In a machine for continuous manufacture of a brush element of the type described, the combination of a stationary mandrel adapted to guide the longitudinal movement of spaced wires along its exterior, means operative to move such wires along said mandrel, a tubular shaft rotatably mounted substantially axially of one end of said mandrel, a drum from which a continuous strand of brush material may be unwound rotatably mounted axially of the other end of said shaft from said mandrel, means on the end of said shaft adjacent said drum adapted to guide a strand of brush material from said drum into said tubular shaft, means on the end of said shaft adjacent said mandrel adapted to wind such strand conducted thereto through said shaft about said mandrel and such brush material wires, means for rotating said shaft, means for rotating said drum, means for securing such brush material to such wires, and means for severing such brush material along a line intermediate of such wires.

15. In a machine for the continuous manufacture of a brush element of the type described, the combination of means adapted to support two continuously moving wires in substantially parallel spaced relation, brush material winding means mounted for rotation about an axis parallel to such moving wires and adapted to wind such material about such spaced wires, and brush material supply means for said winding means comprising a drum adapted to have brush material wound thereon, said drum being mounted substantially axially of said rotatable winding means.

16. In a machine for the continuous manufacture of a brush element of the type described, the combination of means adapted to support two continuously moving wires in substantially parallel spaced relation, brush material winding means mounted for rotation about an axis parallel to such moving wires and adapted to wind such material about such spaced wires, and brush material supply means for said winding means comprising a rotatable drum adapted to have brush material wound thereon, said rotatable drum being mounted substantially axially of said rotatable winding means.

17. In a machine for the continuous manufacture of a brush element of the type described, the combination of at least two spaced parallel conveyor elements adapted to travel in unison, at least one of said conveyor elements being drawn from a supply source and adapted to serve as a brush material retaining member in such finished brush element, and at least one of said conveyor elements being of the endless type and including a return course, winding means operative to wind brush material about said conveyor elements thus traveling in unison, and means adapted to secure such material to said

conveyor element adapted to serve as a retaining member.

18. In a machine for the continuous manufacture of a brush element of the type described, the combination of means adapted to support two continuously moving wires in substantially parallel spaced relation, means adapted to wind brush material about such two spaced wires as the latter advance, thereby forming a succession of loops of brush material about such wires, conveyor means passing within such loops intermediate such wires and adapted to contact and support both sides of such loops internally thereof, said conveyor means being of the endless type having a return course out of contact with such brush material, and means adapted to drive said conveyor means with the brush material supporting portions thereof traveling in the same direction as such wires.

19. In a machine for the continuous manufacture of a brush element of the type described, the combination of means adapted to support two continuously moving wires in substantially parallel spaced relation, brush material winding means mounted for rotation about an axis parallel to such moving wires and adapted to wind such material about such spaced wires, a spindle mounted substantially axially of said winding means, means adapted to wind stranded brush material on said spindle from a supply thereof, means turning with said first-named winding means adapted to unwind such material from said spindle to be conducted to said first-named winding means, and means adapted to drive said spindle to compensate for any differential in the rate at which such brush material is thus wound on said wires and the rate at which such material is unwound from said spindle by said unwinding means.

20. In a machine for continuous manufacture of a brush element, means adapted to support two wires in spaced parallel relation, means adapted continuously to advance such wires in

unison, a rotatable winding arm adapted to wind strands of brush material about such spaced wires, drive means adapted to rotate said arm, a drum mounted for rotation about the same axis of rotation as said arm about which such brush material may be wound prior to passing to said arm, drive means adapted to rotate said drum, and control means automatically operative to regulate the rate of rotation of said drum responsive to tension in such brush material.

21. In a machine for continuous manufacture of a brush element, means adapted to support two wires in spaced parallel relation, means adapted continuously to advance such wires in unison, a rotatable winding arm adapted to wind strands of brush material about such spaced wires, drive means adapted to rotate said arm, a drum mounted for rotation about the same axis of rotation as said arm about which such brush material may be wound prior to passing to said arm, drive means adapted to rotate said drum, a rotatable unwinding arm adapted to turn with said winding arm and unwind such brush material from said drum for delivery to said winding arm, said unwinding arm being adapted for in and out movement generally radially of the axis of rotation, and control means actuated by such movement adapted to regulate said drive means for said drum.

RUBEN O. PETERSON.
